UNITED STATES PATENT OFFICE.

JOHN WILLISON, OF DERBY, ENGLAND, ASSIGNOR TO THE NATIONAL MALLEABLE CASTINGS COMPANY, OF CLEVELAND, OHIO, A CORPORATION OF OHIO.

AUTOMATIC COUPLING FOR RAILWAY-CARRIAGES.

SPECIFICATION forming part of Letters Patent No. 728,184, dated May 12, 1903.

Application filed August 27, 1901. Serial No. 73,491. (No model.)

To all whom it may concern:

Be it known that I, JOHN WILLISON, a citizen of England, residing at No. 1 Olney Villas, Clarence road, Derby, in the county of Derby, England, have invented certain new and useful Improvements in Automatic Couplings for Railway-Carriages, (for which I have applied for a patent in Great Britain, dated July 4, 1901, No. 13,650,) of which the following is a specification.

My invention relates to the construction and mounting of automatic couplings for railway-carriages in such a manner that the coupling-head can be held in certain positions while in the act of coupling, but on being coupled is automatically released, so that it can swing to either side as the carriages run on curves, but is always urged by a spring back to its central position, as I shall describe, referring to the accompanying drawings.

Figure 1 is a longitudinal section of the front part of the frame of a railway-carriage provided with the ordinary draw-hook and its spring and also with an automatic coupler according to my invention. Fig. 2 is a plan, partly sectional, of the automatic coupler and its guides; and Fig. 3 is a transverse section on the line 3 3 of Fig. 2.

In the hollow shank of the coupling-head *a* I suspend from the top a pawl *b*, the upper part of which is embraced by an oblique socket at the rear end of an arm *c*. The front end of this arm is bent to one side and is curved and rests on the tail *d* of the coupler-knuckle *e*. In the lower side of the oblique-sided socket *f*, in which the shank of the coupler can swing to either side, I make two notches *g*, one on each side of the center, to receive the pawl *b*. Usually the coupler-head *a* stands in a central position, being urged to that position by a spring, as will presently be described, and in that position it becomes automatically coupled with the coupler-head of another carriage when it happens that the carriages stand upon a straight part of the track. If, however, the carriages that are to be coupled happen to stand on a curved part of the track, the coupler-head is moved by

hooked rods worked by hand to the one side 50 or the other of the central position until the pawl *b* drops into the one or the other of the notches *g* and holds the coupler-head in the position to which it has been moved until coupling is effected, and then the pawl is disengaged in the following manner: When the knuckle *e* is turned outward in the position ready for coupling, its tail *d* is in such a position that the arm *c* drops to the position shown in dotted lines in Fig. 2, allowing the 60 pawl *b* to enter the one or the other of the notches *g*, and thus to keep the coupler-head *a* in a position to the one side or the other of the center line, as above described. When coupling takes place, the knuckle *e* is pushed 65 back, so that it and its tail *d* take the position shown in Fig. 1. The tail *d* in coming to this position raises the front end of the arm *c*, and the pawl *b* is thus disengaged from the notch *g*, leaving the coupler-head 70 free to swing to the central position or to right or left. The sides of the coupler-shank have two rounded parts *h*, bearing on the rear parts of the socket *f*, either of which can act as a fulcrum for the shank when the 75 head is moved out of center. Between the sides of the yoke *h* of the coupler-shank are arranged the draw-springs *i*, which serve also as buffer-springs when the coupler-head is forced rearward. From the plate *j*, against 80 which the front of the spring *i* bears, a central bolt *k* extends backward through a spring *l* and has on its rear end a nut and washer, against which the rear end of the spring *l* bears. The front end of the spring 85 *l* bears on the bottoms of two half-sockets *m* at the front ends of oblique bars *n*, the rear ends *o* of which can slide loosely in races formed in the ends of a cross-piece *p*, which is clamped on two longitudinal bolts *q*, forming part of the underframe of the carriage. Each of the bars *n* has a rounded hollow, which can work as on a fulcrum on a rounded projection *r* of a piece fixed to the rear end of the coupler-shank. When the coupler-head is moved to either side, so that its shank takes an oblique position, the fulcrum *r* causes 95 the bars *n* and sockets *m* to take such a po-

sition as to compress the spring *l*, so that when the coupler-head is relieved from the force which deflected it the spring *l*, reacting on the sockets *m* and fulcra *r*, urge the coupler-shank to resume its central position. The rear follower *x* of the springs *i* is arranged to act on the long arm of a vertical curved lever *s*, the short arm of which acts on the shank of the ordinary draw-bar *t*, which may have draw-springs of blade form, as shown at *u*, or might have helical draw-springs, such as *i*. The effect of this arrangement is that when the coupler-head *a* is pushed rearward by buffing action it not only compresses the spring *i*, but also pushes it backward, forcing back the lower end of the lever *s*, so that its upper end moves forward the draw-bar *t*, compressing the draw-spring *u*. Thus when the coupler acts as a buffer it has a longer stroke subject to spring action than if it acted only on the coupler draw-spring *i*. As I have in former specifications described this method of increasing the buffer-stroke of an automatic coupler by the use of two side levers like *s*, I make no claim to this in the present case.

Having thus described the nature of this invention and the best means I know of carrying the same into practical effect, I claim—

1. In combination with an automatic coupler for railway-carriages a pawl adapted to engage in notches of the socket in which the coupler-shank can move and an arm embracing the pawl and resting on the tail of the coupler-knuckle, substantially as and for the purpose set forth.

2. In combination with the shank of an automatic coupler for railway-carriages, a spring and a pair of bars having half-sockets against which the spring abuts, free guides for the bars, and fulcra for them projecting from the

rear end of the coupler-shank, substantially as and for the purpose set forth.

3. The combination with a laterally-movable draw-bar, of a latch adapted to hold it in laterally-deflected position, and means actuated by the motion of the parts in coupling and adapted to release said latch; substantially as described.

4. The combination with a laterally-movable draw-bar, of a latch adapted to hold it in laterally-deflected position, and means actuated by the motion of the parts in coupling and adapted to release said latch; and a centering-spring for the draw-bar; substantially as described.

5. The combination with a laterally-movable draw-bar, of a latch adapted to hold it in laterally-deflected position, a knuckle, and an arm adapted to be released by the knuckle when in closed position and to disengage said latch; substantially as described.

6. In combination with the shank and yoke of a coupler for railway-carriages, a centering-spring bearing at the rear of the yoke and adapted to hold the coupler yieldingly in central position; substantially as described.

7. In combination with the shank and yoke of a coupler for railway-carriages, levers extending to the frame of the car, and spring mechanism coacting with the levers and adapted to hold the coupler yieldingly in central position; substantially as described.

In testimony whereof I have hereunto set my hand in presence of two subscribing witnesses.

JOHN WILLISON.
